UNITED STATES PATENT OFFICE.

GEORGE E. GARDNER, OF XENIA, OHIO.

METHOD OF UNITING COMBINED RE-ENFORCE AND OVERLAP PIÈCES TO SHIRT-BODIES.

SPECIFICATION forming part of Letters Patent No. 371,677, dated October 18, 1887.

Application filed July 23, 1885. Serial No. 172,410. (No model.)

To all whom it may concern:

Be it known that I, GEORGE E. GARDNER, of Xenia, Greene county, State of Ohio, have invented a new and useful Improvement in a 5 Method of Uniting a Combined Re-enforce and Overlap Piece to a Shirt-Body, of which the following is a specification.

My invention relates to improvements in apparel shirts, the object being to produce an 10 improved combined re-enforce and overlap piece from a single piece of fabric; and my invention consists in the improved method of uniting an integral combined re-enforce and overlap piece to a shirt-body, as is hereinafter 15 fully described, and specially as pointed out in the claim.

Accompanying this specification, to form a part of it, there are three plates of drawings, containing four figures, illustrating my invention, with the same designation of its parts by 20 letter-reference used in all of them.

Of the illustrations, Figure 1 shows the form of the re-enforce as cut from the fabric, a dotted line indicating the position of a transverse 25 fold made therein to double the re-enforce back on itself to form an overlap for attachment to the slit in the shirt-back, and another dotted line indicating the position of the over-folded part of said re-enforce piece. Fig. 2

30 illustrates the re-enforce piece as folded transversely and centrally attached to the shirt-back at each side of the slit therein, with the upper ends of the parts free, folded over and down to show their relative position, and 35 with the lower overlapping parts of the re-enforce where adjacent to the transverse fold made therein curved outwardly thereat. Fig. 3 shows a plan view of the finished shirt, and Fig. 4 a section taken on the line $\alpha\alpha$ of Fig. 3.

40 The parts containing my invention, and those of the shirt with which it connects, are designated by letter-reference, and the method of cutting and connecting the parts is described as follows:

45 The letter R indicates a re-enforced piece that is cut from the fabric to have in combination the straight edges $e' e^2$ and the oppositely-curved portions $e^3 e^4$, and as thus cut oppositely from the fabric no waste is made.

50 The edges $e' e^2$ are parallel to each other, but at such a distance apart in parallel extension

as is required for the overlap, the dotted line o , indicating a transverse fold-line whereon the fold f' of the re-enforce piece R is folded over and down on the fold f^2 of the latter, as 55 indicated by the dotted line f^3 of Fig. 1. When the re-enforce piece R is thus transversely folded and laid, it is placed over the shirt-back B, with the edge e' parallel with the side a' of the slit, and the edge e^2 overlapping the opposite edge of the slit a^2 . When the parts are thus arranged, the edge e' of the re-enforce is sewed to the side edge, a' , of the slit, and the side a^2 of the slit is sewed to the overlapping part O^2 of the fold f^2 of the re-enforce, as indicated at s^3 . When the edges of the slit are united to the two folds $f' f^2$ of the re-enforce R, suitable hem-folds or turned-in edges are employed in both, excepting where the edge a^2 is connected with the overlap A of the fold 60 f^2 , when the edge of the slit alone is turned in, and the fly-edge of the overlap A is made with a suitable turned-in or hem-folded edge, when used without an exterior facing-strip.

The letter E indicates a facing or additional 75 staying-piece, that is exteriorly sewed along its edges to the overlap A of the fold f^2 and below the fold-line of the re-enforce, so as to form a stay thereat.

The letter S⁴ designates lines of stitching 80 connecting the curved edges of the re-enforce to the shirt-body B, said stitching where crossing the overlap A uniting the folds $f' f^2$ thereat to the shirt-body.

While I have shown the exterior strip, E, 85 used in connection with my improved re-enforce, yet the latter may be applied without it.

I am aware that a single piece of material has been folded and stitched to the sides of the slit in a shirt to constitute an upper and under 90 button lap or fly, a facing and a stay for reinforcing the bottom of the opening; and also that re-enforcing forms have been made in separate pieces and secured to the shirt, one of said pieces being wider and longer than the 95 other, and a stay-piece sewed on the edges and doubled, the crimp or double line forming the bottom of the stay, and I therefore do not claim, broadly, re-enforcing pieces and stays of this construction, my improvements being 100 specifically pointed out in the claim.

Having thus described my invention, what I

claim, and desire to secure by Letters Patent, is—

The method herein described of uniting an integral combined re-enforce and overlap piece to a shirt-body, which consists in cutting the re-enforce piece in a single form-piece, R, having parallel edges $e' e^2$, then sewing the one part, f' , of the re-enforce to the shirt-back with its straight edge e' on the edge of the back-slit 5 of the shirt, then turning the other part, f' , of the re-enforce over and down on the shirt-back to lap the secured re-enforce with its straight edge e^2 parallel with the straight edge e' , then

securing it to the shirt-back by a line of stitches about its edges and along the back-slit of the 15 shirt, and then securing a stay-strip, E, on the outer face of the overlapping re-enforce, substantially as specified.

Signed at Troy, New York, this 2nd day of July, 1885, in the presence of two witnesses 20 whose names are hereto written.

GEO. E. GARDNER.
